UNITED STATES PATENT OFFICE.

RICHARD PEALE, OF ST. BENEDICT, PENNSYLVANIA, ASSIGNOR TO REMBRANDT
PEALE, OF ST. BENEDICT, PENNSYLVANIA.

COAL-MINING MACHINE.

Application filed July 29, 1918. Serial No. 247,212.

To all whom it may concern:

Be it known that I, RICHARD PEALE, a citizen of the United States, residing at St. Benedict, in the county of Cambria and 5 State of Pennsylvania, have invented certain new and useful Improvements in Coal-Mining Machines, of which the following is a specification.

The invention relates to coal mining machines and more particularly to a novel machine for working in relatively soft coals, and which is also adapted to work in relatively thin veins and in veins of different thicknesses, and having general adaptability 15 to the different kinds of mining work.

Further objects and advantages of the invention will be set forth in part hereinafter, and in part will be obvious herefrom or may be ascertained through practice with the 20 invention.

The invention consists in the novel parts, constructions, arrangements, combinations and improvements herein shown and described.

25 The accompanying drawings, herein referred to and constituting a part hereof, illustrate one embodiment of the invention, and together with the description serve to explain the principles thereof.

30 On the drawings:

Fig. 1 is a side elevation, with a part of the bottom frame broken away, and with parts in section, of a machine embodying the invention;

35 Fig. 2 is a top plan corresponding to Fig. 1, but with parts broken away and with parts in section;

Fig. 3 is a front elevation looking at Figs. 1 and 2 from the left;

40 Fig. 4 is a fragmentary detail of a flexible cutter;

Fig. 5 is a section, on an enlarged scale, on line 5-5 of Fig. 3;

45 Fig. 6 is a detached and somewhat diagrammatic plan of another form of conveyor especially adapted for very thin coal veins;

Fig. 7 is a like side elevation of the same conveyor, and looking at Fig. 6 from the 50 bottom side thereof;

Fig. 8 is a fragmentary sectional detail of the top cutter drive;

Fig. 9 is a fragmentary detail, partly in section showing two clutches on the driving

shaft for the side cutters, whereby one cutter 55 may be driven alone;

Fig. 10 is a fragmentary transverse section, taken on the line 10-10 of Fig. 2, with parts omitted for the sake of clearness.

The machine of my invention is adapted 60 for practically all kinds of mine work, being capable of entry or gangway driving or excavating and also being capable of both room and long wall work. In certain aspects, the machine is especially designed for 65 work in coal which is relatively soft or friable, or which has well defined vertical cleavage planes, whereby the coal is caused to break off into fragments and to fall down of its own weight as the machine advances, 70 and is not completely cut off by the machine as is the case with some other kinds of mining machines. With my invention there is no need of completely cutting the coal free 75 from the vein, thereby avoiding much work and much breakage of the coal. Nor is there need of an intermediate conveying or transferring device for the coal between the dislodging or breaking off mechanism and the usual conveyor, as the forward travel of 80 the entire machine effects this without the necessity of providing any special means or mechanism therefor.

Means are provided by the invention for cutting in the coal a horizontal kerf at the 85 top of the vein, and another horizontal kerf at the bottom of the vein, and cooperating therewith separate means for cutting vertical kerfs connecting the kerfs at the top and bottom of the vein. The body of coal thus 90 partially detached or defined that is, cut around by the kerf cutters, will of its own weight then disintegrate in fragments of a desirable size, easy for handling but without undesirable and wasteful pulverizing, 95 and will fall downwardly within the machine. The machine thus takes advantage of the natural cleavage faces or planes and the soft nature of the coal to avoid much of the mechanical work of cutting and undue breakage. The broken and fallen coal is pushed on to an internally located conveyor by the advancing movement of the machine, which movement also keeps the cutters to their work in the kerfs. Other features of the 100 invention will be pointed out hereinafter, or will be apparent herefrom. Not only is the machine adaptable to entry or gangway 105

work and to room or long wall work, but it leaves behind flat vertical walls, and takes out clean at one operation all the coal from the bottom to the top of the vein.

Referring in detail to the accompanying drawings, illustrating by way of example one embodiment of the invention, a carriage 1 is provided comprising a flat base plate or platform 2, which platform is provided with power means for traveling it forwardly and backwardly, and at its forward end supports, preferably in fixed position the cutter supporting and guiding frames. The embodied form of traveling means comprises a caterpillar or other endless tread 3 arranged longitudinally beneath the platform 2, to support and to travel the machine, the tread being protected by the platform.

Mounted on platform 2 is a motor 4, which in the present embodiment furnishes all the power for driving the different parts of the machine as well as for traveling the machine itself. I accomplish this mounting of the motor by means of brackets 4^a and 4^b, fastened to the motor and to the frames 61 and 62, respectively, which are fixed to and extend upwardly from the platform 2 as later described. The drive for the endless tread comprises a worm or helical gear 5 on the shaft 6 of the motor 4, with which gear meshes a corresponding gear 7 on a shaft 8. On shaft 8 is a worm 9, with which meshes a worm gear 10 on a vertical shaft 11, journaled in the machine frame. Shaft 11 has a bevel gear 12 with which meshes a bevel gear 13 fixed on shaft 14 of roller 15. Shaft 14 is journaled in bearings on the bottom side of platform 2, and its roller 15 serves to drive the tread 3.

At its other end the endless tread 3 passes about a guiding roller 16, the shaft 17 of which is journaled in the machine frame or in brackets on the carriage platform 2. A suitable clutch 18 is provided on shaft 8 to throw out the drive if it is desired to run the motor and keep the machine stationary.

In the embodied form, the kerf cutters are in fixed relation to the machine, that is they have no necessary travel or movement relatively to the machine in doing their work, but in the present preferred form the cutters are advanced through the coal by the forward travel of the machine.

As embodied, a bottom kerf cutter is provided comprising a rigid guide frame with side reaches 25 which extend forwardly from both sides of the platform 2. At its front the guide frame has a straight cross reach 26 and at the back a corresponding cross reach 24. Running in the guideway formed by the reaches 24, 25 and 26 is a flexible cutter 27 having links 28 and cutting teeth 29 set at different angles therein in a well-known manner, whereby the kerf is cut sufficiently wide to provide clearance for the

guide frame 25 to pass into the kerf. In detail the guide frame may have side plates 30 and 31 with lips 32 and 33, respectively, to hold and guide links 28. Spacing and backing blocks 34 and 36 are provided at the back, having bolts 35 and 37 or other suitable fastening means.

The embodied form of driving means for the bottom kerf cutter comprises a bevel gear 40 on the forward end of the shaft 6 of motor 4 (this mechanism also driving other parts). Meshing with gear 40 is a bevel gear 41, which gear is loose on a shaft 42, arranged across the machine and journaled in bearings 46. Fixed to the gear 41 is a clutch member 43, and a cooperating clutch member 44 is keyed by a key 45 to rotate with, while slidably along, shaft 42. On shaft 42 is fixed a bevel gear 52, with which meshes a bevel gear 53, the gear 53 being fixed on a vertically disposed shaft 54, which shaft is journaled on the machine frame. Fixed on shaft 54 is a sprocket wheel 55, which engages with and drives the endless flexible cutter 28. Idler sprockets 63 and 64 are provided at the forward end at the juncture of the side reaches with the front cross reach of the cutter guide. A similar driving mechanism for the cutter is preferably provided at the opposite end of shaft 42, and is so shown, but need not be described in further detail.

Cooperating with the bottom kerf cutter is a top kerf cutter, which is substantially in vertical alignment above the bottom cutter and the construction of which may be substantially the same as the bottom cutter and need not be described in further detail. In accordance with one feature of the invention, the top cutter may be raised and lowered to work in veins of different thicknesses, and by such change in level, the machine is able at one operation and at one advance of the machine to entirely cut about all the coal between the top and bottom of the vein. As embodied, the rigid guide frame 56 for the endless flexible cutter 57 at the rear part of its side reaches and along the back cross reach 58 is fixed to and supported upon a frame 59, extending along underneath the guide frame 56. Forwardly extending brackets 60 may also be used to further support the side guide frames. Each side frame 59 is supported by, but is vertically movable with respect to, frames 61 and 62 fixed to and extending upwardly from the platform 2 at each side thereof.

To provide for changing the height of the top cutter, as embodied, the side frames 59 are each provided with downwardly projecting legs 65 and 66, working in guideways in the bottom frame plate 61. Each frame 59 has similar legs 67 and 68, working in like guideways in the bottom frame 62. The legs 65-68 are provided with suit-

130

able fastening devices to hold the top frame at the desired level, and as embodied, each leg has spaced apart holes therein, through which may pass bolts 69, which also pass 5 through holes in the respective bottom plates 61 and 62, to support the top cutter at the desired height.

Means are provided for driving the top kerf cutter, and in the present embodiment, 10 such driving means are combined with the means or devices for raising and lowering the top frame, cooperating with the adjustable or positionable legs 65-68 already described. In such embodied form there is 15 provided at each side or rear corners of the top kerf cutter frame a vertically disposed shaft 75, which may be alike in structure and connections, and description of one shaft will suffice for both. Shaft 75 is journaled in bearings in a bracket 76 carried upon the machine frame, a collar 78 holding the shaft 75 in longitudinal position with respect to its bearings 76. The shaft 75, for the purpose of driving the top cutter, 20 is provided at its bottom end with a beveled gear 77, which gear meshes with a beveled gear 52, on shaft 42, already described. At its upper end, shaft 75 is journaled in the frame plate 59, already described, the shaft 25 being longitudinally extensible and contractible to accommodate the changes in height of the top cutter frame. To drive the top cutter 57, shaft 75 is provided at its upper end with a driving sprocket wheel 80, meshing 30 with the endless flexible cutter 57, already described. The upper portion of the shaft is kept from longitudinal displacement in suitable manner, as by the hub of the sprocket wheel 80 bearing on a journal 35 support in the plate 59.

Referring now to the means for lengthening and shortening the driving shaft 75, the shaft is centrally or intermediately divided into two parts, the lower part having an internal screw thread 81 and the upper part 45 having an internal screw thread 82, one of these screw threads being left-handed and the other being right-handed. Screwed into the interior of the two parts of the shaft 75 is 50 a screw threaded rod 83, provided at or near its center with a solid nut or turning head 84. Jam nuts 85 and 86 are threaded on the screw rod 83, to be jammed against both ends of the separated shaft 75 to lock the 55 parts in position. By turning the solid nuts 84 on each shaft 75, the upper kerf cutter frame is raised or lowered as desired.

Means are provided for maintaining the 60 shaft 75 integral or fixed throughout during the driving of the cutters, but permitting of the screw movement between the parts of the shaft to effect changes in elevation. As embodied, keys 87 and 88 are provided for 65 the two parts, respectively, of the shaft 75,

these keys fitting into a slot in the shaft and entering a longitudinal groove in the screw shaft 83. These hold the parts fixed for driving, but are removed preparatory to screwing the shaft to make it longer or 70 shorter. Thus when the keys 87 and 88 are removed, the screw rod 83 may be turned by means of the head 84 in either direction to raise or lower the top cutter and its frame. When the proper height is reached, 75 the keys 87 and 88 are inserted in their slots, and pass into the grooves in the shaft 83. Jam nuts 85 and 86 are screwed against the ends of the two parts of the shaft 75, and the shaft is then solid to rotate and drive 80 the cutter.

A similar driving and lifting and lowering mechanism is provided at the opposite side of the machine, which may be the same or similar in construction, and need not be described in further detail.

Means are provided for making in the veins of coal vertical kerfs or cuts connecting the horizontal top and bottom kerfs or cuts, either at one or both sides, or substantially connecting them, so that the coal included between the kerfs or cuts will progressively and continuously break off and fall of its own weight without being cut away from the vein at the back. The coal on breaking away from the vein falls within the machine, and mechanism is provided for conveying the dislodged and broken coal backwardly as the machine advances and as the cutting progresses into the vein. In soft or friable coal, the coal breaks readily of its own weight, and this is likewise true of somewhat harder coal having well defined planes or faces of vertical cleavage. In entry work, and in some room or breast work, 105 both side cutters will be employed, while in other room, entry, or breast work, and in long-wall work, but one side or vertical cutter need be used.

In accordance with one feature of the invention, the side kerf cutters are made vertically extensible and contractable for veins of different thicknesses, to enable the side cuts to reach the top horizontal cut or kerf irrespective of variations in the height of the top cutter. In the embodied form, the side cutters are provided with rigid guide frames for their respective endless flexible cutters, each of said frames having a stationary bottom reach 93, and a vertical reach 94 integral therewith or fixed thereto.

The reaches 93 are bolted on to the corresponding side plates 61, and near their rear ends have preferably also supports or bearings, respectively, from the platform 2. An inclined reach 95 of each guide is fixed to and supported by a bracket 96, which bracket is journaled on the shaft 42. The reaches 93 and 95 are in vertical alinement at their rear ends to provide a continuous guide for 120 125 130

the flexible cutter, and are provided with angular clearance at their juncture so that the bracket 96 may be swung upwardly and downwardly.

5 The reach 95 at its forward end is adapted to receive extension pieces 97, which are interchangeable one with another but of different lengths, and the vertical reach 94 is adapted to take at its top end extensible 10 sections 98, likewise interchangeable and of different lengths. The backing member 36 (Fig. 5) in the forward end of each of the reaches 95 and 94, is cut short or determined, and the corresponding member of the 15 various sized extensions 97 and 98 have their members 36 of extra length the member 34 on one part and the member 36 on the other part overlapping, and the bolts 37 in such case holding them together. The 20 upper forward turn of the vertical flexible cutter is provided for by a member having an idler sprocket, the shaft of which is shown at 100, over which sprocket the cutter runs. The sprocket carrying member 25 has two pivoted parts 101 and 102, shaped to open and close angularly, to conform to the angular separation of the reaches 93 and 95 of the conveyor guide. The extension pieces 97 and 98 are attachable to and 30 detachable from the corner piece 101, 102 in the manner already described for the members 94 and 95. The side cutters are driven from the rear end and for this purpose the flexible cutters 103 mesh with a 35 sprocket 104 fixed on the shaft 42.

The side kerf cutters at each side may be substantially the same in construction and the description need not be duplicated. The clutch mechanism 43, 44 may be duplicated 40 or, as shown in Fig. 9, to provide for running one side or vertical cutter without the other when desired, or the flexible cutter may be taken off from one side when not required in the operation of the machine. 45 In practical work the change in elevation and in the operation of the cutters are relatively infrequent, as such machines are usually employed for long periods upon the same kind of work.

50 Referring now to the means for conveying away the dislodged and broken coal, in the present preferred embodiment, a platform 110 is provided within the frame of the lower horizontal cutter, which platform 55 may be carried upon a roller or other support 111. Communicating backwardly from the platform 110 is an endless belt conveyor 112, shown in Fig. 1 (omitted from Fig. 2 for clearness) as passing rearwardly 60 through the central part of the machine and over the motor casing 4. At its forward end the conveyor runs over a guiding roller 113, and at its rear end over a driving roller 114, journaled in brackets 119 and 120 65 supported on the motor casing. The convey-

or may be provided with one or more sets of guiding and supporting rollers 115 and 116. In the embodied form of drive, a worm wheel 117 meshes with a worm 5 on the motor shaft 6. The worm wheel 117 is 70 fixed upon a shaft 118, journaled in the brackets 119 and 120, already referred to. The shaft 118 is provided with a clutch 121 for controlling the operation of the conveyor.

75 A second reach of the conveyor may extend backwardly and the forward guiding and driving roll therefor is indicated by 122 in Fig. 1.

In Fig. 6 of the drawing an arrangement 80 of conveyors is shown, the showing being largely diagrammatic, where the dislodged and broken coal is fed out sidewise. In this form the forward reach of the conveyor 125 is located within the cutters in the position 85 of the platform 110. The conveyor 126 is located at the side of the machine, the coal being fed out transversely and obliquely by means of a baffle plate 127. A pivotally mounted reach 129 of the conveyor leads to 90 the car 130. This form of conveyor will be found useful in low veins, that is veins of small thickness where there is not sufficient space for the conveyor and the coal thereon to pass over the top of the motor casing. To 95 provide clearance above the conveyor belts 125 and 126 for the coal, the reach 93 of the vertical cutter guide may be removed or other suitable provision made and a bridge plate 131 may be employed between the 100 conveyors 125 and 126.

The machine will thus operate in veins 105 of widely different thicknesses and will work in very thin veins, and will always cut kerfs close to the top and bottom, with clean vertical cuts at the side. The machine is also capable of doing the opening up work, that is, cutting out entries and gangways, and will also make the leading cuts for room or breast work and for long-wall work as 110 well. It will equally readily do the following up work with a loose end or open side, either in room work, entry work, or long-wall work. The whole weight and momentum of the machine is employed to hold the 115 cutters to the work, and it is not required to fasten the machine to the walls or top or bottom. The machine is also readily and rapidly shiftable by its own power from place to place in the work. For shifting the machine sidewise a windlass or drum 120 135 is formed on shaft 6 of the motor. A hook may be placed over the bottom frame forwardly and a pulley block rigged on a post or block, and a rope run from the hook through the block and about the drum 135 and the machine drawn sidewise sliding along the tread 3 to the desired place. The machine is run backwardly or forwardly by reversing the direction of the tread 3 by 130

reversing the motor or in other suitable or convenient manner.

The invention in its broader aspects is not limited to the details of construction shown and described, but changes may be made therefrom without departing from the principles of the invention and without sacrificing its chief advantages.

What I claim is:—

10. 1. A coal mining machine including in combination a horizontal top chain kerf cutter, a horizontal bottom chain kerf cutter, vertical chain kerf cutters at either side, a platform extending rearwardly of the cutter chain frames, a motor mounted on said platform, a caterpillar tread for traveling the machine, located at the rear of the machine beneath the platform and of less width than the cutters, and driving connections from the motor to said cutters and to said tread.

20. 2. A coal mining machine including in combination a horizontal top chain kerf cutter, a horizontal bottom chain kerf cutter, vertical chain kerf cutters at either side, a platform extending rearwardly of the cutter chain frames, a motor mounted on said platform, a caterpillar tread for traveling the machine, located at the rear of the machine beneath the platform and of less width than the cutters, said tread terminating near the rear of the bottom cutter chain, and a conveyor for the dislodged coal, with its forward end in advance of the caterpillar tread and at substantially the level of the bottom kerf cutter, and extending rearwardly and upwardly through the machine.

30. 3. A coal mining machine including in combination a horizontal top chain kerf cutter, a horizontal bottom chain kerf cutter, vertical chain kerf cutters at either side, a platform extending rearwardly of the cutter chain frames, a motor mounted on said platform, a caterpillar tread for traveling the machine, located at the rear of the machine beneath the platform and of less width than the cutters, said tread terminating near the rear of the bottom cutter chain, and a conveyor for the dislodged coal, with its forward end in advance of the caterpillar tread and at substantially the level of the bottom kerf cutter, and extending rearwardly and upwardly through the machine, and a platform within the bottom kerf cutter frame and in front of the forward end of said conveyor.

40. 4. A coal mining machine including in combination a top kerf cutter, a bottom kerf cutter, means for varying the distance between said cutters for veins of different sizes, vertical kerf cutters at each side and a cutter guide frame and interchangeable sections therefor to permit varying the length of cut of the side cutters to substantially connect the top and bottom kerfs to permit the coal to break off and fall.

5. A coal mining machine including in combination a top kerf cutter, a bottom kerf cutter, means for varying the distance between said cutters for veins of different sizes, vertical kerf cutters at each side and a cutter guide frame and interchangeable sections therefor to permit varying the length of cut of the side cutters to substantially connect the top and bottom kerfs to permit the coal to break off and fall, and means for driving the cutters.

6. A coal mining machine including in combination a top kerf cutter, a bottom kerf cutter, means for varying the distance between said cutters for veins of different sizes, vertical kerf cutters at each side, a cutter guide frame and interchangeable sections therefore to permit varying the length of cut of the side cutters to substantially connect the top and bottom kerfs to permit the coal to break off and fall, means for driving the cutters and for advancing the machine to keep the cutters to the work.

7. A coal mining machine including in combination a carriage traveling on the mine bottom, a bottom kerf cutter mounted on the carriage and extending forwardly, a top kerf cutter mounted on the carriage and extending forwardly substantially in line with the bottom cutter, and means for raising and lowering the top kerf cutter to operate at the top of veins of different thicknesses, and means for making a vertical side kerf of varying length so as to substantially connect the top and bottom cuts to permit the coal to break off and fall.

8. A coal mining machine including in combination a horizontal top chain cutter, a horizontal bottom chain cutter, vertically disposed chain cutters at either side of the top and bottom cutters, said cutters being mounted in fixed relation longitudinally of the machine, means for vertically raising and lowering the top kerf cutter to operate at the top of veins of different thicknesses, the side chain cutters being extensible and contractible to correspond to the vertical changes in height of the top cutter.

9. A coal mining machine including in combination a horizontal top chain kerf cutter, a horizontal bottom chain kerf cutter, vertical chain kerf cutters at either side, a platform extending rearwardly of the cutter chain frames, a motor mounted on said platform, a caterpillar tread located within the width of the cutter guide frames, beneath the platform and at the rear of the machine, and of less width than the cutters, and driving connections from the motor to the cutters and the tread.

10. A coal mining machine including in combination a carriage, means frictionally engaging directly with and thereby traveling the carriage over the mine bottom, a motor on the carriage, mechanism mounted on the

carriage including a plurality of endless cutter chains for cutting a horizontal top kerf, a bottom kerf, and a side kerf ahead of the carriage, the side kerf cutting mechanism being in fixed relation longitudinally of the machine, to permit the coal to break off and fall, and connections from the motor for simultaneously driving the cutters and traveling the carriage forward as the cutting advances.

11. A coal mining machine including in combination a carriage, means frictionally engaging directly with and thereby traveling the carriage over the mine bottom, a motor on the carriage, mechanism mounted on the carriage including a plurality of endless cutter chains for cutting a horizontal top kerf, a bottom kerf, and a side kerf ahead of the carriage, the side kerf cutting mechanism being in fixed relation longitudinally of the machine to permit the coal to break off and fall, and connections from the motor for simultaneously driving the cutters and traveling the carriage forward as the cutting advances, and a conveyor located within the space bounded by the cutters and driven by the motor to move the broken off coal backwardly.

12. A coal mining machine including in combination an endless chain horizontal top kerf cutter, an endless chain horizontal bottom kerf cutter in substantial vertical alinement, an endless chain vertical cutting means with its cutting reach substantially in alinement with the top and bottom kerf cutting reaches, and substantially connecting the top and bottom kerfs to permit the coal to break off and fall, all said chains having cutting reaches to cut a kerf, the cutting reaches of the chains being maintained in substantially the same vertical plane at the front of the machine, and means for simultaneously driving the cutters and advancing the machine.

13. A coal mining machine including in combination an endless horizontal top kerf cutter, an endless horizontal bottom kerf cutter in substantial vertical alinement, endless vertical cutting means substantially connecting the top and bottom kerfs to permit the coal to break off and fall, means for simultaneously driving the cutters and advancing the machine, a cutter guide frame and interchangeable sections therefor to permit varying the height of the top cutter, and means for correspondingly extending the vertical cutting means for veins of different thicknesses.

14. A coal mining machine including in combination a top kerf endless chain cutter, a bottom kerf endless chain cutter, means for cutting a vertical kerf substantially connecting the top and bottom kerfs to permit the core to break, and means for traveling the machine forward as it cuts, a platform

back of the bottom cutter to receive the coal as it breaks off and falls, and a rearwardly extending conveyor located behind and receiving the coal from the platform, the coal being forced thereonto by the forward travel of the machine.

15. A coal mining machine including in combination a carriage, endless chain cutters including horizontally disposed top and bottom chain cutters, at the front of the carriage in fixed relation thereto, the cutters permitting the coal to break off from the vein, and a conveyor on the carriage leading backwardly therefrom, means frictionally engaging directly with the mine bottom for driving the cutters and for traveling the carriage forward to keep the cutters to the work and for forcing the fallen and broken coal on to the conveyor.

16. A coal mining machine including in combination an endless flexible horizontal top kerf cutter, an endless flexible horizontal bottom kerf cutter in substantial vertical alinement, and endless flexible vertical cutting means substantially connecting the top and bottom kerfs to permit the coal to break off and fall, the bottom and side cutter means being in fixed relation in substantially the same vertical plane at the front of the machine, and means for simultaneously driving the cutters and advancing the machine.

17. A coal mining machine including in combination an endless flexible horizontal top kerf cutter, an endless flexible horizontal bottom kerf cutter in substantial vertical alinement, endless flexible vertical cutting means substantially connecting the top and bottom kerfs to permit the coal to break off and fall and means for simultaneously driving the cutters and advancing the machine, a cutter guide frame and interchangeable sections therefor to permit varying the height of the top cutter, and means for correspondingly extending the vertical cutting means for veins of different thicknesses.

18. A coal mining machine including in combination a carriage, a bottom and top endless chain kerf cutter at the front of the carriage, vertical kerf cutting means at one side of the top and bottom cutters, and substantially connecting the top and bottom kerfs to permit the coal to break off and to fall, the front of the side cutter being fixed in substantially the same vertical plane as the top and bottom cutters, means for driving the machine to its work, a traction tread and means on the carriage for simultaneously driving the cutters and the tread.

19. A coal mining machine including in combination a carriage located beneath, within and at the rear of the machine, a caterpillar tread for the carriage, a bottom and a top endless chain kerf cutter at the front of

the carriage, vertical kerf cutting means substantially connecting the top and bottom kerfs to permit the coal to break off and to fall, a conveyor on the carriage extending from near the bottom cutter for conveying away the fallen coal, and means on the carriage for simultaneously driving the cutters, conveyor and the tread.

20. A coal mining machine including in combination a carriage located beneath, within and at the rear of the machine, a caterpillar tread for the carriage frictionally engaging directly with the mine bottom, a bottom and a top endless chain kerf cutter at the front of the carriage and in fixed relation thereto, vertical kerf cutting means substantially connecting the top and bottom kerfs to permit the coal to break off and to fall, and means on the carriage for simultaneously driving the cutters and the tread.

21. A coal mining machine including in combination a carriage located beneath, within and at the rear of the machine, a caterpillar tread for the carriage, a bottom and a top endless chain kerf cutter at the front of the carriage and in fixed relation thereto, vertical kerf cutting means substantially connecting the top and bottom kerfs to permit the coal to break off and to fall, a conveyor on the carriage extending from near the bottom cutter for conveying away the fallen coal, and means on the carriage for simultaneously driving the cutters, conveyor, and the tread.

22. A coal mining machine including in combination a carriage located beneath, within and at the rear of the machine, a caterpillar tread for the carriage, a bottom and a top endless chain kerf cutter and vertical cutting means substantially connecting the top and bottom kerfs to permit the coal to break off and fall, a platform back of the bottom cutter to receive the fallen coal, a conveyor extending backwardly from the platform, and means on the carriage for simultaneously driving the cutters and the tread to keep the cutters to the work and to force the fallen coal from the platform on to the conveyor.

23. A coal mining machine including in combination a carriage located beneath, within and at the rear of the machine, a caterpillar tread for the carriage, a bottom and a top endless chain kerf cutter at the front of the carriage, and in fixed relation thereto, vertical kerf cutting means substantially connecting the top and bottom kerfs to permit the coal to break off and to fall, a platform back of the bottom cutter to receive the fallen coal, a conveyor extending backwardly from the platform, and means on the carriage for simultaneously driving the cutters and the tread to keep the cutters to the work and to force the fallen coal from the platform on to the conveyor.

24. A coal mining machine including in combination a carriage, kerf cutting mechanism comprising a rigid guide supported by and extending forwardly from the carriage at the top of the vein, and a flexible cutter running in the guide, a rigid guide supported by and extending forwardly from the carriage at the bottom of the vein and a flexible cutter running therein, rigid vertical guides at each side carried by and extending forwardly from the carriage, said guides being in fixed position longitudinally on the frame, flexible cutters running therein, and means for driving the cutters.

25. A coal mining machine including in combination a carriage, kerf cutting mechanism comprising a rigid guide supported by and extending forwardly from the carriage at the top of the vein, and a flexible cutter running in the guide, a rigid guide supported by and extending forwardly from the carriage at the bottom of the vein and a flexible cutter running therein, rigid vertical guides at each side carried by and extending forwardly from the carriage, said guides being in fixed position longitudinally on the frame, flexible cutters running therein, and means for driving the cutters, and means for advancing the carriage to keep the cutters to the work.

26. A coal mining machine including in combination a carriage, kerf cutting mechanism comprising a rigid guide supported by and extending forwardly from the carriage at the top of the vein, and a flexible cutter running in the guide, means for raising and lowering the top guide for veins of different thicknesses, a rigid guide supported by and extending forwardly from the carriage at the bottom of the vein and a flexible cutter running therein, rigid vertical guides at each side carried by and extending forwardly from the carriage, cutters running in the vertical guides and means for driving the cutters.

27. A coal mining machine including in combination a carriage, kerf cutting mechanism comprising a rigid guide supported by and extending forwardly from the carriage at the top of the vein, and a flexible cutter running in the guide, means for raising and lowering the top guide for veins of different thicknesses, a rigid guide supported by and extending forwardly from the carriage at the bottom of the vein and a flexible cutter running therein, rigid vertical guides at each side carried by and extending forwardly from the carriage, cutters running in the vertical guides a cutter guide frame and interchangeable sections therefor to permit extending or contracting the vertical side guides to conform to the position of the top guide, and means for driving the cutters.

28. A coal mining machine including in

- combination a carriage, a horizontally disposed endless top kerf cutter frame mounted thereon, means for vertically raising and lowering the frame without disturbing its horizontal relation, comprising an elevating device between the carriage and frame, guides at each side of the elevating device, and cutter driving means at the rear end of the cutter frame.
- 10 29. A coal mining machine including in combination a carriage, a horizontally disposed endless top kerf cutter frame mounted thereon, and extending forwardly therefrom, means for raising and lowering the frame without disturbing its horizontal relation, comprising an elevating device between the carriage and frame, guides at each side of the elevating device, and cutter driving means at the rear end of the cutter frame.
- 15 30. A coal mining machine including in combination a carriage, a horizontally disposed endless top kerf cutter frame mounted thereon, means for raising and lowering the frame without disturbing its horizontal relation, comprising an elevating device between the carriage and frame, comprising members at each side of the carriage, guides at each side of the elevating device, and cutter driving means at the rear end of the cutter frame.
- 20 31. A coal mining machine including in combination a carriage, a horizontally disposed endless top kerf cutter frame mounted thereon, means for raising and lowering the frame, without disturbing its horizontal relation, comprising an elevating device between the carriage and frame, comprising screw rods at either side of the carriage, guides at each side of the elevating device, and cutter driving means at the rear end of the cutter frame.
- 25 32. A coal mining machine including in combination, a horizontal top guideway and an endless chain cutter running therein, a horizontal bottom guideway and an endless chain cutter running therein, a vertical guideway in fixed position longitudinally of the machine and making a kerf substantially connecting the top and bottom cutters and having an endless chain cutter running therein, means for simultaneously driving the cutters and means simultaneously and gradually advancing the machine.
- 30 33. A coal mining machine including in combination a horizontal top guideway and an endless chain cutter running therein, a horizontal bottom guideway and an endless chain cutter running therein, a vertical guideway in fixed position longitudinally of the machine and making a kerf substantially connecting the top and bottom cutters and having an endless chain cutter running therein, means for simultaneously driving the cutters and means for varying the distance between the top and bottom cutters.
- 35 34. A coal mining machine including in combination a horizontal top guideway and an endless chain cutter running therein, a horizontal bottom guideway and an endless chain cutter running therein, a vertical guideway in fixed position longitudinally of the machine and making a kerf substantially connecting the top and bottom cutters and having an endless chain cutter running therein, means for simultaneously driving the cutters and means simultaneously and gradually advancing the machine and a motor simultaneously driving the cutters and the machine advancing means.
- 40 35. A coal mining machine including in combination a horizontal top guideway and an endless chain cutter running therein, a horizontal bottom guideway and an endless chain cutter running therein, a vertical guideway in fixed position longitudinally of the machine and making a kerf substantially connecting the top and bottom cutters and having an endless chain cutter running therein, means for simultaneously driving the cutters and traction means resting upon the mine bottom simultaneously and gradually advancing the machine, and a motor simultaneously driving the traction advancing means and the cutters.
- 45 36. A coal mining machine including in combination a horizontal top guideway and an endless chain cutter running therein, a horizontal bottom guideway and an endless chain cutter running therein, a vertical guideway in fixed position longitudinally of the machine and making a kerf substantially connecting the top and bottom cutters and having an endless chain cutter running therein, means for simultaneously driving the cutters and means simultaneously and gradually advancing the machine, and a cutter guide frame and interchangeable sections therefor to permit varying the vertical distance between the top and bottom cutters while maintaining the driving connections therefor.
- 50 37. A coal mining machine including in combination cooperating kerf cutters positioned to cut below, above and at the side of a block of coal, a platform at the rear of the machine, a motor on the platform, a caterpillar tread for advancing the machine and pressing the cutters to the work, and driving connections at the rear of the machine between the motor and tread.
- 55 38. A coal mining machine including in combination cooperating kerf cutters positioned to cut below, above and at the side of a block of coal, a drive of the entire machine keeping a forward working pressure on the cutters and means for varying the distance between the top and bottom cutters,

traction means resting upon the mine bottom simultaneously and gradually advancing the machine.

70 34. A coal mining machine including in combination a horizontal top guideway and an endless chain cutter running therein, a horizontal bottom guideway and an endless chain cutter running therein, a vertical guideway in fixed position longitudinally of the machine and making a kerf substantially connecting the top and bottom cutters and having an endless chain cutter running therein, means for simultaneously driving the cutters and means simultaneously and gradually advancing the machine and a motor simultaneously driving the cutters and the machine advancing means.

75 35. A coal mining machine including in combination a horizontal top guideway and an endless chain cutter running therein, a horizontal bottom guideway and an endless chain cutter running therein, a vertical guideway in fixed position longitudinally of the machine and making a kerf substantially connecting the top and bottom cutters and having an endless chain cutter running therein, means for simultaneously driving the cutters and traction means resting upon the mine bottom simultaneously and gradually advancing the machine, and a motor simultaneously driving the traction advancing means and the cutters.

80 36. A coal mining machine including in combination a horizontal top guideway and an endless chain cutter running therein, a horizontal bottom guideway and an endless chain cutter running therein, a vertical guideway in fixed position longitudinally of the machine and making a kerf substantially connecting the top and bottom cutters and having an endless chain cutter running therein, means for simultaneously driving the cutters and means simultaneously and gradually advancing the machine, and a cutter guide frame and interchangeable sections therefor to permit varying the vertical distance between the top and bottom cutters while maintaining the driving connections therefor.

85 37. A coal mining machine including in combination cooperating kerf cutters positioned to cut below, above and at the side of a block of coal, a platform at the rear of the machine, a motor on the platform, a caterpillar tread for advancing the machine and pressing the cutters to the work, and driving connections at the rear of the machine between the motor and tread.

90 38. A coal mining machine including in combination cooperating kerf cutters positioned to cut below, above and at the side of a block of coal, a drive of the entire machine keeping a forward working pressure on the cutters and means for varying the distance between the top and bottom cutters,

- and driving means for the kerf cutters located at the rear end thereof.
39. A coal mining machine including in combination cooperating kerf cutters positioned to cut below, above and at the side of a block of coal, and a caterpillar tread located to the rear of, and transversely narrower than the top and bottom kerfs for advancing the machine and pressing the cutters to the work and means for varying the distance between the top and bottom cutters. 5 70
40. A coal mining machine including in combination cooperating kerf cutters positioned to cut below, above and at the side of a block of coal, and a forward drive for the entire machine keeping working pressure on the cutters and means for varying the distance between the top and bottom cutters, and a cutter guide frame and interchangeable sections therefor to permit varying the vertical length of cut of the side cutter to substantially connect the kerfs made by the top and bottom cutters. 10 75
41. A coal mining machine including in combination cooperating kerf cutters positioned to cut below, above and at the side of a block of coal, a cutter guide frame and interchangeable sections therefor to permit varying the vertical length of cut of the side cutter to substantially connect the kerfs made by the top and bottom cutters, and driving means for the machine located at its rear and within the width of the horizontal kerfs. 15 80
42. A coal mining machine including in combination a horizontal top guideway and an endless chain cutter running therein, a horizontal bottom guideway and an endless chain cutter running therein, a vertical guideway at the side of the machine and substantially connecting with the top and bottom cutters and having an endless chain running therein, means for changing the distance between the top and bottom cutter guides, and a cutter guide frame and interchangeable sections therefor to permit extending the length of cut of the vertical cutter to substantially connect the top and bottom kerfs irrespective of such changes in position of the top and bottom guides. 20 85
43. A coal mining machine including in combination a horizontal top guideway and an endless chain cutter running therein, a horizontal bottom guideway and an endless chain cutter running therein, a vertical guideway at the side of the machine and substantially connecting with the top and bottom cutters and having an endless chain running therein, means for changing the distance between the top and bottom cutter guides, and a cutter guide frame and interchangeable sections therefor to permit extending the length of cut of the vertical cutter to substantially connect the top and bottom kerfs irrespective of such changes in 25 90
44. A coal mining machine including in combination top, bottom and side cutter guides mounted in fixed relation to the machine, cutters running therein, and means for varying the distance between the top and bottom guides and a cutter guide frame and interchangeable sections therefor to permit correspondingly varying the length of cut of the side cutter to maintain the three kerfs in cooperative relationship, and traction means traveling the entire machine forward to press the cutters to the work. 30 95
45. A coal mining machine including in combination top, bottom and side cutter guides mounted in fixed relation to the machine, cutters running therein and means for varying the distance between the top and bottom cutter guides and a cutter guide frame and interchangeable sections therefor to permit correspondingly varying the length of cut of the side cutter to maintain the three kerfs of such dimensions and in such positions as to substantially join, and friction tread means located at the rear of, within and beneath the machine and traveling the entire machine forward to press the cutters to the work. 35 100
46. A coal mining machine including in combination a carriage traveling on the mine bottom, horizontal flat bottom and top guides mounted on and extending forwardly from the carriage and with their fronts in substantially the same vertical plane, endless chain kerf cutters running therein, means for vertically raising and lowering the top guide and cutter to operate at the top of veins of different thicknesses and means adjustable for making a vertical side kerf substantially connecting the top and bottom kerfs irrespective of their distance apart. 40 105
47. A coal mining machine, including in combination a motor, a carriage bearing the motor, a tread beneath, at the rear of and narrower than the carriage, a flat bottom guide extending forwardly from the carriage, a flat horizontal top guide extending forwardly from the carriage, flexible chain cutters running in said guides, means for raising and lowering the top guide and cutter for veins of different heights and a side cutter making a kerf substantially connecting the top and bottom kerfs and extensible 45 110
48. A coal mining machine, including in combination a motor, a carriage bearing the motor, a tread beneath, at the rear of and narrower than the carriage, a flat bottom guide extending forwardly from the carriage, a flat horizontal top guide extending forwardly from the carriage, flexible chain cutters running in said guides, a side cutter 50 115

- making a kerf substantially connecting the top and bottom kerfs, and a conveyor between the cutters and running backwardly on the carriage.
5. 49. A coal mining machine including in combination cooperating kerf cutters positioned to cut below, above and at the side of a block of coal, a platform at the rear of the machine, a motor thereon, and a flat traction tread drive for the entire machine extending beneath said platform and within the width and at the rear of the cutters.
50. A coal mining machine including in combination cooperating kerf cutters in fixed relation with each other longitudinally of the machine, and positioned to cut below, above and at the side of a block of coal, a platform at the rear of the machine, a motor thereon, and a flat traction tread drive for the entire machine located beneath the platform.
51. A coal mining machine including in combination a horizontal top guideway and an endless chain cutter running therein, a horizontal bottom guideway and an endless chain cutter running therein, a vertical guideway in fixed position at the side of the machine and having an endless chain cutter running therein, and a flat traction tread drive for the machine resting upon the mine bottom and located at the rear of the machine and advancing the machine and pressing the cutters to the work.
52. A coal mining machine including in combination a horizontal top guideway and an endless chain cutter running therein, a horizontal bottom guideway and an endless chain cutter running therein, a vertical guideway at the side of the machine and having an endless chain cutter running therein, and a flat traction tread drive for the machine resting upon the mine bottom and located at the rear of the machine and advancing the machine and pressing the cutters to the work, and driving means for the chains located at the rear ends of the guideways.
53. A coal mining machine including in combination top, bottom and side cutter guides mounted in fixed relation to the machine, cutters running therein, and a flat traction tread located beneath and at the rear, and driving the entire machine forward to press the cutters to the work.
55. 54. A coal mining machine including in combination top, bottom and side cutter guides mounted in fixed relation to the machine, cutters running therein, and flat endless traction tread means located at the rear of, within and beneath the machine and traveling the entire machine forward to press all the cutters to the work.
55. A coal mining machine, including in combination a motor, a carriage bearing the motor, a flat, endless traction tread beneath, at the rear of and narrower than the carriage, a flat bottom guide extending forwardly from the carriage, a flat horizontal top guide extending forwardly from the carriage, flexible chain cutters running in said guides, and a side cutter making a kerf substantially connecting the top and bottom kerfs.
56. A coal mining machine including in combination a machine frame, a horizontally disposed top kerf cutting chain, a horizontally disposed bottom kerf cutting chain, a vertically disposed side kerf cutting chain cooperating therewith, guideways for the cutting chains mounted in fixed position longitudinally of the frame, a motor on the frame, an endless traction tread at the rear of and beneath the frame and engaging directly with the floor to drive the frame forward and thereby to press the cutting chains to the work, and driving connections from the motor to the cutting chains and to the tread.
57. A coal mining machine including in combination a machine frame, a horizontally disposed top kerf cutting chain, a horizontally disposed bottom kerf cutting chain, a vertically disposed side kerf cutting chain cooperating therewith, guideways for the cutting chains mounted in fixed position longitudinally of the frame, means for changing the vertical position of the top kerf cutting chain, and means whereby the side cutter chain is correspondingly changed, a motor on the frame, an endless traction tread at the rear of and beneath the frame and engaging directly with the floor to drive the frame forward and thereby to press the cutting chains to the work, and driving connections from the motor to the cutting chains and to the tread.

In testimony whereof, I have signed my name to this specification.

RICHARD PEALE.
